UNITED STATES PATENT OFFICE.

ROBERT MULRONE, OF CAMPERDOWN, SYDNEY, NEW SOUTH WALES, AUSTRALIA.

DESIGN FOR A TOY HORSE WITH JOCKEY.

58,251.

Specification for Design.

Patented June 28, 1921.

Application filed December 28, 1920. Serial No. 433,654. Term of patent 7 years.

To all whom it may concern:

Be it known that I, ROBERT MULRONE, a citizen of New South Wales, Australia, residing at Camperdown, Sydney, State of New South Wales, Australia, have invented a new, original, and ornamental Design for a Toy Horse with Jockey, of which the following is a specification, reference being had to the accompanying drawings, forming part thereof.

The figure is a plan view of a toy horse with jockey showing my new design.

I claim:

The ornamental design for a toy horse with jockey, as shown.

ROBERT MULRONE.

Witness:

THOS. HAMMOND.
